US00D847365S

(12) **United States Design Patent** (10) **Patent No.:** **US D847,365 S**
(45) **Date of Patent:** **** Apr. 30, 2019**

(54) **MICROBIAL AIR SAMPLER**

(71) Applicant: **Veltek Associates, Inc.**, Malvern, PA (US)

(72) Inventor: **Arthur L. Vellutato, Jr.**, Malvern, PA (US)

(73) Assignee: **Veltek Associates, Inc.**, Malvern, PA (US)

(**) Term: **15 Years**

(21) Appl. No.: **29/580,760**

(22) Filed: **Oct. 12, 2016**

Related U.S. Application Data

(63) Continuation of application No. 14/807,642, filed on Jul. 23, 2015, now Pat. No. 9,513,278, which is a continuation of application No. 13/930,967, filed on Jun. 28, 2013, now Pat. No. 9,121,845, which is a continuation of application No. 12/685,770, filed on Jan. 12, 2010, now Pat. No. 8,474,335.

(57) **CLAIM**

The ornamental design for a microbial air sampler, as shown and described.

DESCRIPTION

FIG. 1 is a perspective view of a microbial air sampler showing my new design;

FIG. 2 is a top view thereof;

FIG. 3 is a bottom view thereof;

FIG. 4 is a front view thereof; and,

FIG. 5 is a cross-sectional side view thereof.

The left and right side views are the same images as the front view.

1 Claim, 2 Drawing Sheets
